UNITED STATES PATENT OFFICE.

JOHN C. GABEL, JR., OF ONARGA, ILLINOIS.

DOOR-HANGER AND TRACK THEREFOR.

SPECIFICATION forming part of Letters Patent No. 654,619, dated July 31, 1900.

Application filed October 25, 1899. Serial No. 734,775. (No model.)

To all whom it may concern:

Be it known that I, JOHN C. GABEL, Jr., of Onarga, in the county of Iroquois and State of Illinois, have invented a new and Improved 5 Door-Hanger and Track Therefor, of which the following is a full, clear, and exact description.

My invention relates to that class of tracks designed as overhead supports for sliding 10 doors and in connection with which a track for the bottom of the door is not used and is not needed.

One object of the invention is to simplify the construction of such tracks and to provide 15 the track with means whereby a door provided with rigid hangers when over the opening designed to be closed will be automatically and quickly placed in position in said opening.

Another object of the invention is to so construct a suspension-track for sliding doors, especially car-doors, that the hangers of the 20 door will be protected from the weather, whereby the door will not be directed to the opening it is designed to close until it is in position to uninterruptedly enter said opening, and whereby the door may be opened or closed without manually moving the door either outward or inward or at an angle to 25 the frame in connection with which the door is used.

The invention consists in the novel construction and combination of the several parts, as will be hereinafter fully set forth, 30 and pointed out in the claims.

Reference is to be had to the accompanying drawings, forming a part of this specification, in which similar characters of reference indicate corresponding parts in all the figures.

Figure 1 is a side elevation of a portion of a car and a front elevation of a door for the same, illustrating the improved suspension-track applied to the door and the door as closed, a portion of the side of the car being broken 40 away. Fig. 2 is a horizontal section through the improved track and portion of the side of the car, illustrating the door in plan view and open. Fig. 3 is a section taken practically on the line 3 3 of Fig. 1, showing the 45 door closed. Fig. 4 is an enlarged perspective view of a portion of the improved track, a part of the said track being broken away.

Fig. 5 is a vertical section taken substantially on the line 5 5 of Fig. 2. Fig. 6 is a view of the closed end of the track or the end that is 55 nearest the opening designed to be closed by a door, and Fig. 7 is a detail perspective view of a door-hanger.

A represents the side of a car; B, the sliding door, designed to cover an opening C in the 60 car, and D represents the improved suspension-track. This track is usually made from one piece of material, although it may be otherwise constructed, and comprises an upper longitudinal vertical flange 10, adapted 65 to be secured to a surface by screws or otherwise, an outwardly-extending upper member 11, which may be horizontal, as shown in Fig. 5, or inclined, as shown in Fig. 4, a downwardly-projecting vertical front member 12, and a 70 lower horizontal member 13 of less width than the upper member 11, which lower member 13 is provided with an upwardly-extending longitudinal flange 14 at its inner edge, which forms a guideway with the member 12. A 75 space intervenes between the upper edge of the flange 14 and the upper main member 11, and the end of the track which is adjacent to the opening to be closed by the door is covered by a cap 15. (Illustrated in Fig. 6.) 80

The door B is provided with two hangers E and E'. These hangers are secured to the outer face of the door B at the top, as shown in Figs. 1, 2, and 3, the hanger E being near the edge of the door that is farthest removed 85 from the opening to be closed by the door. The hanger E is preferably constructed as shown in Fig. 7, comprising a vertical shank 18, adapted for attachment to the door by screws or other devices, and an upper outwardly-extending member 19, having a downwardly-projecting flange 20 at its outer or free end. The upper member 19 of the hanger E is preferably somewhat curved, although it may be straight, if desired. When the 90 hanger is attached to the door, the upper member 19 extends through the space between the flange 14 of the lower section 13 of the track and the upper section 11, as shown in Fig. 4, and the projection or lip 20 on the hanger is 95 of sufficient length to rest or bear upon the inner surface of the said lower member 13 of the track, as is also shown in Fig. 4. The hanger E' differs from the opposing hanger E only in 100

the shape of its upper member 19^a, which member instead of extending at a right angle from the shank is curved in direction of the edge of the door adjacent to which the hanger is placed, as shown in Figs. 2 and 3. The member 19^a of the hanger E' is curved in the manner stated in order to insure the door traveling a sufficient distance in the track D to bring the door immediately opposite the opening C, into which it is to be fitted. The door is guided into this opening by locating a partition 17 in the suspension-track D at its closed end, and, as shown in Figs. 2 and 3, this partition extends from the end cap of the track to the front section 12, connecting with this section of the track at a point quite close to the closed end of the track, so that the partition 17 is very short. This partition may constitute an integral portion of the track or may be secured therein in any suitable or approved manner. When the suspension-track D is in position, its closed end is substantially opposite the outer jamb of the door-frame or that jamb into which the bolt 25 would be entered, and the track extends above the door-frame a suitable distance beyond the opposite jamb, as shown in Figs. 1, 2, and 3.

The door is usually provided with one or more studs 21 at what may be termed its "forward vertical edge," and these studs are adapted to enter recesses in the jamb of the door-frame, as is shown in Fig. 1, serving as bolts; but the opposite vertical edge portion of the door is secured to the car-body by means of a lock 23 of any suitable construction. The door is prevented from sliding off the track at its open end by locating a suitable stop 24 on the body of the car below the open end of the track, as shown in Fig. 1, and in order to facilitate handling the door said door is provided with a hand-grip 22 of any suitable character.

In operation, the door being open, as shown in Fig. 2, when it is desired to close the door said door is simply pushed in direction of the closed end of the track D, and as soon as the member 19^a of the hanger E' engages with the inclined partition 17 the door will be directed into the opening C it is designed to close, and the door is held in its closed position by reason of the said hanger E' engaging with the track D where the partition 17 engages with its closed end, as illustrated in Fig. 3. When the door is to be opened, it is simply drawn in direction of the open end of the track, and when so drawn the partition 17 will permit the door to travel outward or forward and then horizontally along the track. When the door is in its open position, the pendent portions 20 of the hangers engage with the suspension-track at the front, as shown in Figs. 2 and 4; but when the door is closed the said members 20 of the hangers engage with the suspension-track D at the lower flange 14, as shown in Fig. 3. In the drawings I have illustrated the track as provided with transverse

strengthening-webs 16; but said webs may be omitted, if desired.

Having thus described my invention, I claim as new and desire to secure by Letters Patent—

1. A suspension-track for doors, consisting of upper and lower spaced-apart members connected at the front, the lower member being provided with an upwardly-extending flange at its inner edge, and a partition in the lower member at one end thereof, said partition extending in an inclined direction from the front toward the flange, as described. 80

2. A suspension-track for sliding doors, comprising upper and lower members connected at the front, the lower member being provided with an upwardly-extending flange at its inner edge, which flange is of less depth vertically than the vertical space between the upper and lower members of the track, means for closing one end of the track, and an inclined plane located at the closed end of the track, extending from the front in direction of the flange of the lower member of said track, as described. 90

3. The combination, with a suspension-track, consisting of an upper member, a lower member of less width and provided with a flange at its inner edge, whereby a space intervenes between the said flange and the said upper member, and a front member connecting the upper and lower members, the said track being closed at one end, and a vertical partition located at the closed end of the track, extending from the front thereof in direction of the flange of the lower member of the track, of a door, hangers secured to the said door, said hangers having members arranged to enter the track at the space between the flange of its lower member and the upper member of the track, the entering member of the hanger nearest the said partition having a curvature in direction of the partition, and projections from the forward ends of each hanger, which projections are arranged for engagement with the bottom portion of said track, as described. 110

4. The combination of a suspension-track having two spaced-apart longitudinally-extending vertical members forming a guideway between them, a partition extending across said guideway at one end thereof in an inclined direction, and a door having hangers formed with horizontal members loosely fitted in said guideway, one of said hangers engaging said partition when the door is being closed, and being guided thereby to its seat, as set forth. 115

5. The combination of a suspension-track having an upper member arranged for attachment to a car or the like, a vertical front member and a lower member connected to said front member and having a longitudinal flange forming a guideway with said front member and spaced from the side of the car and said upper member, a partition extending in an inclined direction across said guideway. 120

way, and a door having hangers secured thereto, said hangers being formed with horizontal members having projections at their free ends adapted to ride on the lower member, one of said hangers engaging with the partition when the door is closed, as set forth.

5 In testimony whereof I have signed my

name to this specification in the presence of two subscribing witnesses.
